TELEPHONE-EXCHANGE SYSTEM.

1,373,447.

Specification of Letters Patent.

Patented Apr. 5, 1921.

Application filed February 12, 1920. Serial No. 358,173.

To all whom it may concern:

Be it known that I, LIPA POLINKOWSKY, a citizen of Russia, residing at Antwerp, Belgium, have invented certain new and 5 useful Improvements in Telephone-Exchange Systems, of which the following is a full, clear, concise, and exact description.

This invention relates to telephone exchange systems and particularly to systems 10 employing selectively operable switching devices for establishing talking connections between subscribers' lines.

The object of this invention is the provision of a switch controlling mechanism 15 comprising a register arranged to respond to a plurality of series of impulses for determining the selection and operation of the automatic switches used in establishing connections.

20 A feature of the invention relates to a switch controlling mechanism in which a register is positioned responsive to a series of impulses to select one of a plurality of automatic switches, and is then again positioned responsive to a succeeding series of 25 impulses to control the selective operation of such automatic switch.

Further features of the present invention 30 will become obvious from the following description and appended claims.

In the drawings, Figures 1 and 2, taken in order, illustrate a portion of a telephone system embodying the invention. Fig. 1 discloses two subscribers' lines together 35 with a pair of non-numerical or finder switches for extending these lines. Fig. 2 shows two selective switches joined by means of a link circuit with the finder switches in Fig. 1 and which serve to complete the extension of calling lines to the 40 lines of called subscribers. There is also shown in Fig. 2 a switch controlling mechanism comprising a register for determining the selection and operation of the selective switches.

The present invention is particularly applicable to small private branch exchange systems of the full automatic type where only a comparatively few selective operations are necessary for the establishment 50 of talking connections. It will be understood, however, that the invention is not limited to either small capacity systems or to systems of the full automatic type. In

the disclosure there is shown a switching 55 arrangement adapted to accommodate a private branch exchange having twenty subscribers' lines. These lines are arranged in two groups of ten lines each. All the lines in the first group, such as line 200, appear 60 as calling lines in the multiple contacts of line finder switches, such as the switch 210. All lines in the second group, such as line 205, appear in the multiple contacts of line 65 finder switches, such as switch 220. The 65 finder switches 210 and 220 comprise a line finding unit arranged to extend any one of the twenty lines to a link circuit 202, 203 and 206. For this purpose the contacts of 70 finder switch 210, such as contacts 216, 217 and 218 and the contacts of finder 220, such as contacts 225, 226 and 227 are connected to the corresponding conductors 202, 203 and 206 of the link circuit. When a call is initiated in the first group of ten lines 75 the switch 210 is automatically operated to select the calling line and extend it to the link circuit. When, however, a call is initiated in the second group of ten lines, 80 finder switch 210 is first operated and upon reaching a given position causes the operation 85 of the line finder switch 220, which thereupon automatically selects the calling line and extends it to the link circuit 202, 203 and 206.

The link circuits extending from the contacts of the line finder switches, terminate in contacts such as 284, 285 and 286 of the selective switch 280, and in contacts such as 294, 295 and 296 of the selective switch 90 290. In a manner similar to the arrangement of the line finder switches, the selective switches 280 and 290 comprise a final connecting unit. The switch 280 serves to complete connections to one of the groups 95 of ten subscribers' lines and switch 290 serves to complete connections to the other group of ten lines. In addition to this, two positions of the switch 290 are reserved for the completion of connections to trunk lines 100 leading from the private branch exchange to the central office.

A switch controlling mechanism comprising a multi-position register is provided for selecting one or the other of the switches 105 280 and 290 and also for controlling the operation of the selected switch to complete the connection to the called line.

The line finder switches 210, 220, the selective switches 280, 290, the controlling register 100 and the sequence switch 250 used in the present system may be of the type disclosed in the patent to Reynolds and Baldwin No. 1,127,808. In Fig. 1 the contacts located within the area bounded by the vertical broken lines are controlled respectively by the correspondingly located switches 210 and 220. In Fig. 2 the contacts to the right of the right hand vertical broken line are controlled by switch 290, the contacts between the two vertical broken lines are controlled by switch 280, the contacts within the small broken rectangle inclosing register 100 are controlled by such register and the remaining switch contacts are controlled by the sequence switch 250.

It is believed that a clearer understanding is to be had of the invention by describing in detail the establishment and release of a telephone connection. For this purpose it is first assumed that the subscriber of line 200 in the first group of ten lines desires to converse with the subscriber of line 208, which is also located in the first group of ten lines. For convenience the first group of ten lines is numbered consecutively from 10 to 19 and the second group of lines is numbered consecutively from 20 to 29. Hence, the first, or tens digit of all lines in the first group is 1 and the first digit of all lines in the second group is 2. Upon removing the receiver from the switch hook the subscriber of line 200 closes a circuit from battery through the winding of common start relay 204, left-hand winding of line relay 201, contact and inner armature of cut-off relay 207, over the loop of the calling line to ground at the outer armature and contact of relay 207. Relay 201 attracts its armature and closes a path from battery through the winding of relay 207, right-hand winding and contact and armature of relay 201 to the contact 218 of the line finder switch 200. Relay 204 by energizing closes a circuit from ground through its contact and armature, conductor 211, contact 243 (1) of sequence switch 250, armature and contact of relay 238, winding of slow-to-energize relay 233 to battery and ground. A parallel branch of this circuit is also closed by way of the armature and back contact of relay 231, resistance 212, windings of slow-to-energize relay 234 to battery and ground. Relays 233 and 234 attract their armatures after an interval. Relay 234 completes a circuit from battery through the right-hand winding of relay 239, contact 236 (1), front contact and armature of relay 234, contact 235 (1), back contact and armature of relay 264 to ground. Relay 239 becomes energized in this circuit and establishes the following circuit for operating the line finder switch 210; bat-

tery through the winding of magnet of switch 210, contact 214, contact 224 (1) of switch 220, conductor 221, contact 249 (1), front contact and armature of relay 239, contact 238 (1), contact and armature of relay 233, conductor 222, contact 223, contact 213 to ground. The finder switch 210 starts from whatever position it happens to be standing in and commences to rotate in search of the calling line. As the finder switch 210 passes through each of its half positions the upper contact 213 is closed to ground. On reaching position 1½ the above traced path from battery through the winding of cut-off relay 207 to contact 218 is completed by way of conductor 206, contact 246 (1), left-hand winding of test relay 264, conductor 215, contact 213 (1½) to ground. The contact 218 is so arranged that it is closed in its successive positions simultaneously with closure of contacts 213 in the corresponding half positions. Hence, as the finder switch approaches position 2 the circuit just traced is completed and relay 207 becomes energized. Relay 264 energizes in the circuit including its left-hand high resistance winding and completes a holding circuit through its right-hand low resistance winding and front contact and armature for cut-off relay 207 and line relay 201. This low resistance circuit to ground reduces the potential on contact 218 to render the line busy. Relay 264 at its back contact opens the above traced circuit for the energization of relay 239. Relay 239 retracts its armature and completes a circuit from battery through the winding of sequence switch 250, contact 240 (1), back contact and armature of relay 239, contact 238 (1), contact and armature of relay 233, conductor 222, contact 223, contact 213 (2) to ground. Sequence switch 250 advances from position 1 to position 3. It will be observed that the circuit traced from sequence switch 250 depends upon the front contact and armature of relay 233. The circuit of this relay is opened at the armature and contact of relay 204 as soon as the cut-off relay 207 is operated to open the circuit of said relay 204. Relay 233, however, being slow to deenergize does not release its armature until after relay 239 has had time to deenergize and complete the circuit for moving sequence switch 250 into position 3. On reaching position 2 sequence switch 250 closes a direct circuit to ground at contact 219 for maintaining the energization of relay 207 and relay 201. The finder switch 210 is thus brought to rest on the contacts of the calling line 200, the operating circuit of said switch being opened by the deenergization of relay 239.

In position 3 of the sequence switch 250 the impulse relay 231 is energized in series with the calling line by means of a circuit

from battery through the left-hand winding of coil 242, left-hand winding of relay 231, contact 244 (2 to 6), conductor 202, finder contact 216, over the loop of the calling substation finder contact 217, conductor 203, winding of slow-to-release relay 268, contact 245 (2 to 6), right-hand winding of relay 231, middle winding of coil 242 to ground. Relay 231 becomes energized in series with the calling line and closes a circuit from ground, contact 243 (3), armature and front contact of relay 231, armature and back contact of relay 239, contact 240 (3), left-hand winding of relay 239, winding of register 100 to battery and ground. A circuit is also closed from battery through the right-hand winding of relay 239, contact 241 (3), front contact and armature of relay 231 to ground at contact 243. Relay 239, being differential, does not operate when both of its windings are energized simultaneously. The register 100, however, becomes energized in series with the left-hand winding of relay 239 and moves out of position 0. Between position 0 and position 1 the master contact 101 of register 100 closes a direct circuit to ground in shunt of the left-hand winding of differential relay 239. The current flowing in the right-hand winding of relay 239 is now sufficient to energize said relay. The register 100 under the control of its master contact continues to move into position 1.

It may be well to explain at this point that the register 100 is provided with ten controlling positions, one for each of the numerals from 0 to 9. This register responds to the series of impulses sent from the calling subscriber's dial and advances into a position corresponding to the number of impulses contained in the series. The register having assumed a certain position, dependent upon the number of impulses transmitted, later runs through the remaining of its ten positions to normal to control the selection and operation of the selective switches 280 and 290. It will be seen, therefore, that the number of positions passed through by the register in reaching its normal position is the complement of the number of impulses sent from the calling subscriber's dial to set the register. In order that the switches may be controlled in accordance with the digits of called numbers as listed in the directory, it is only necessary to arrange the subscribers' dials such that series of impulses corresponding to the complements rather than to the actual digits themselves are transmitted to the register. The subscribers' dials are further arranged such that the last interruption of the line in each impulse series is comparatively longer than preceding interruptions. The purpose for this will appear hereinafter.

The register 100 having been moved, as

explained, to position 1, nothing further occurs until the subscriber commences to send impulses. In position 3 of sequence switch 250 a circuit is closed from battery through the right-hand winding of tone coil 242, contact 276 (3), interrupter 247 to ground. Current flowing in this circuit produces a characteristic sound in the receiver at the calling substation to advise the calling subscriber that the apparatus is in condition to receive impulses. The calling subscriber thereupon manipulates his dial 228 to send the tens series of impulses corresponding to the first digit of the called number. Since the called line belongs to the first group, the tens digit is 1 and consequently the tens series comprises nine impulses. When the calling line is opened for the first impulse, relay 231 de-energizes. The release of relay 231 opens the circuit for the right-hand winding of differential relay 239, which in turn de-energizes. On the next closure of the line circuit at the completion of the first impulse, the above traced circuit is established for register 100. This register advances from position 1 into position 2, and the relay 239 is energized, as above explained. At the completion of the second impulse, relay 239 de-energizes and the register 100 advances into its next position. This method of operation continues until the last impulse of the series is transmitted, at which time register 100 will have reached position 9. During each brief interruption of the circuit of relay 231, a circuit is completed from battery through the windings of relay 234, resistance 212, back contact and armature of relay 231, contact 243 (3) to ground. The relay 234 being slow to energize does not attract its armature in response to the short closures of this circuit. At the last impulse of the series, however, relay 231 remains de-energized for a sufficient period to permit the energization of relay 234. Relay 234 completes a circuit from battery through the winding of sequence switch 250, contact 253 (3), front contact and armature of relay 234, contact 235 (3) to ground. Sequence switch 250 moves out of position 3. When sequence switch 250 reaches position 6 a circuit is closed from battery through the right-hand winding of relay 239, contact 241 (6), back contact and armature of relay 264 to ground. Relay 239 becomes energized and closes a circuit from battery through the winding of register 100, contact 102, contact 249 (6), front contact and armature of relay 239, front contact and armature of relay 231, contact 243 (6) to ground. Register 100 energizes in this circuit and advances from position 9 to its normal position 0. It is not necessary to maintain sequence switch 250 in position 6 since the register 100 will have sufficient time to advance 130

from either of its positions 8 or 9 to its normal position during the period that sequence switch 250 is passing through position 6. Consequently when sequence switch 250 reaches position 6 a circuit is closed from battery through the winding of said sequence switch, contact 255 (6 to 7), back contact and armature of relay 234, contact 235 to ground. Sequence switch 250 thereupon advances over position 6 and position 7 into position 9. In passing out of position 6, contacts 244 and 245 open the circuit of the impulse relay 231. This circuit is again energized upon sequence switch 250 reaching position 8, and relay 231 is included in series with the calling line.

With the sequence switch 250 in position 9 and relay 231 energized, a circuit is completed from battery through the winding of register 100, left-hand winding of relay 239, contact 240 (8 to 9), back contact and armature of relay 239, front contact and armature of relay 231, contact 243 to ground.

At the same time the above traced circuit for the right-hand winding of differential relay 239 is closed to ground at contact 243. The register 100 energizes in the above circuit and advances from position 0 into position 1. The calling subscriber now operates his dial in accordance with the units digit. The register 100 is advanced from position to position, as described, in response to the units series of impulses. On the last comparatively long interruption of the line, relay 234 attracts its armature and closes a circuit from battery through the winding of sequence switch 250, contact 253 (9), front contact and armature of relay 234,

contact 235 to ground. Sequence switch 250 moves out of position 9 and into position 10. After relay 234 has become deenergized in position 10 of sequence switch 250, a circuit is closed from the winding of said sequence switch, contact 255 (10), back contact and armature of relay 234, contact 235 to ground. Sequence switch 250 thereupon advances from position 10 into position 11. In position 11 of sequence switch 250 the selective switch 290, having access to the group of lines containing the called line is started in operation. The circuit for operating this switch may be traced from battery through the winding of the

55 magnet of said switch, back contact and right-hand armature of relay 274, back contact and armature of relay 262, contact 255 (11), back contact and armature of relay 234, contact 235 to ground. Switch 290

60 moves from position 1 over positions 2, 3 and 4 and into position 5, positions 2 and 4 being reserved as above noted for central office connections. In passing position 4, contact 293 is closed to complete a circuit

65 from battery through the winding of reg-

ister 100, contact 102, contact 293 (4½), contact 283 closed in position 1, contact 254 (11), back contact and armature of relay 264 to ground. The register 100 energizes in this circuit and moves forward one position. The switch 290 continues to rotate and in each of its half positions the contact 293 is closed to advance the register 100 one position. This procedure continues until register 100 has been fully restored to its normal position 0. In position 0 of register 100 a circuit is closed from battery through the winding of relay 234, conductor 229, contact 104 (0), contact 256 (11) to ground. Relay 234 attracts its armature and completes a circuit from battery through the winding of sequence switch 250, contact 253 (11), front contact and armature of relay 234, contact 235 to ground. By means of this circuit the sequence switch 250 moves out of position 11 and into position 13.

The selective switch 290 is now in the proper position to close the link circuit through to the called line by way of contacts 294, 295 and 296. While sequence switch 250 is passing through position 12, a test is made to determine the busy or idle position of the called line 208. The circuit for performing this test may be traced from ground, contact 256 (12), left-hand high resistance winding of test relay 264, contact 246 (4 to 16), conductor 232, contact 296, conductor 237, winding of cut-off relay 209 to battery and ground. If the line is idle a full potential will be present on conductor 237, and relay 261 becomes energized by means of its high resistance winding. Relay 261 attracts its armature and completes a substitute circuit to ground through its right-hand low resistance winding. This low resistance path decreases the potential on the test conductor 237 of the called line to render this line non-selectable by other switches. In position 13 of sequence switch 250 a circuit is closed from battery through the winding of said sequence switch, contact 240 (13), back contact and armature of relay 239, front contact and armature of relay 231, contact 243 to ground. The sequence switch 250 moves from position 13 into position 15.

In position 15 of sequence switch 250 ringing current is applied to the called line by means of the following circuit: ringing source 251, contact 266 (15), contact 295 of switch 290, over the lower conductor of the called line 208 and returning by way of the upper conductor of the called line to contact 294 of switch 290, contact 265 (15), conductor 229, windings of relay 234 to battery and ground. The relay 234 is made marginal to the ringing current so as not to operate in series with the bell at the called station. When the called subscriber removes his receiver from the switchhook, the re-

130

sistance of the called line loop is reduced, as is well understood, to permit the energization of relay 234. Relay 234 completes a circuit from battery through the winding 5 of sequence switch 250, contact 253 (15), front contact and armature of relay 234, contact 235 to ground. Sequence switch 250 advances from position 15 into position 16. Position 16 of sequence switch 250 is the 10 talking position. Battery is supplied to the calling line through the winding of relay 231 and to the called line through the windings of relay 262 and contacts 265 and 266.

15 After conversation has been completed and the calling subscriber hangs up his receiver, the supervisory relay 268 is de-energized. A circuit is then completed from battery through the winding of relay 233, 20 contact and armature of relay 268, contact 243 to ground. Relay 233 attracts its armature and closes a circuit from battery through the winding of sequence switch 250, contact 253 (16), contact and armature of 25 relay 233, conductor 222, contact 223, contact 213 to ground. Sequence switch 250 advances into position 17. On leaving position 16 sequence switch 250 opens at contact 219 the holding circuit for the line relay 201 and cut-off relay 207. These relays become de-energized to permit the initiation 30 of further calls by the subscriber of line 200. With sequence switch 250 in position 17 and the called line relay 262 de-energized, a circuit is closed as follows for the restoration 35 of the selective switch 290 to its normal position: battery through the winding of the magnet switch 290, back contact and right-hand armature of relay 274, back contact 40 and armature of relay 262, contact 238 (17), contact and armature of relay 233, conductor 222, contacts 223 and 213 to ground. The switch 290 rotates back to its normal position. As the switch 290 reaches 45 position 18 a circuit is closed from battery through the right-hand winding of relay 262, contact 105 (0) of register 100, contact 293 (18), contact 283 of switch 280, contact 254 (17), back contact and armature 50 of relay 264 to ground. Relay 262 attracts its armature to open the driving circuit of the selective switch 290. This switch, however, under the control of its master contact advances into position 1. When relay 55 262 attracts its armature a circuit is established from battery through the winding of sequence switch 250, front contact and armature of relay 262, contact 238 (17), contact and armature of relay 233, conductor 222, contacts 223 and 213 to ground. Sequence switch 250 advances into position 1, in which position relays 262 and 233 are 60 released.

If the called line 208 is busy at the time 65 sequence switch 250 passes through position 12, the testing position, the test relay 264 does not energize on account of the reduced potential on the test conductor 237. In position 13 relay 239 is energized by means of a circuit from battery through the right-hand winding of said relay, contact 241 (13), back contact and armature of relay 264 to ground. Sequence switch 250, therefore, comes to rest in position 13 instead of continuing to advance into the ringing position, 15. In position 13 of sequence switch 250 a circuit is closed from ground through the interrupter 257, contact 276 (13), right-hand winding of tone coil 243 to battery and ground. The interrupter 257 causes the impression of a characteristic tone on the calling line to notify the calling subscriber that the called line is already busy. The calling subscriber then replaces his receiver to the switchhook and relay 268 becomes de-energized. The de-energization of relay 268 causes the energization of relay 233 in the manner above described. The selective switch 290 is thereupon restored to its normal position by means of the circuit above 80 traced, including the back contacts and armatures of relays 274 and 262 and contact 238 (13). When switch 290 reaches position 18, relay 262 becomes energized as described and closes a circuit from battery through the winding of sequence switch 250, front contact and armature of relay 262, contact 238 (13), contact and armature of relay 233, conductor 222, contacts 223 and 213 to ground. Sequence switch 250 advances from position 13 into position 15. Since the calling subscriber has replaced his receiver to the switchhook, relay 231 is de-energized and the following circuit is closed for the energization of relay 234: battery 90 through the winding of said relay, resistance 212, back contact and armature of relay 231, contact 243 (15) to ground. Relay 234 completes a circuit from battery through the winding of sequence switch 250, contact 253 (15) front contact and armature of relay 234, contact 235 to ground. Sequence switch 250 moves from position 15 into position 16. Sequence switch 250 is driven from position 16 into position 17 by means of a circuit from battery through the winding of said sequence switch, contact 253 (16), contact and armature of relay 233, conductor 222, contacts 223 and 213 to ground. In position 17, relay 262 being again energized in the circuit above traced including contacts 105, 293, 283, 254 and the back contact and armature of relay 264, a circuit is closed from battery through the winding of sequence switch 250, front contact and armature of relay 262, contact 238 (17), front contact and armature of relay 243, and thence to ground by way of conductor 222 and contacts 223 and 213. Sequence switch 250 thereupon moves into its normal position 1. 100

110

120

125

130

The case will now be considered in which it is desired to extend a connection to a subscriber's line belonging to the second group of ten lines. These lines are selected by 5 means of switch 280 and appear accordingly in contacts, such as 284, 285 and 286 of switch 280. To illustrate the operation of the line finder switch 220, it will be further considered in connection with this call that 10 the calling subscriber belongs to the second group of ten lines, one of which lines is shown at 205. The ten lines of the second group appear as calling lines in the contacts of finder switch 220, such as contacts 225, 15 226 and 227. Upon the removal of the receiver from the switchhook, the line relay 260, individual to the calling line 205, is operated in series with the common start relay 204. Relay 204 operates in the manner 20 already described to start the line finder switch 210 in rotation. Since the calling line 205 does not appear in the contacts of the first line finder switch 210, this switch will continue to rotate until it reaches position 25 12. In passing through position 11, switch 210 shifts the driving circuit from the first line finder 210 to the second line finder 220. This circuit may now be traced from ground through the contact 213 (10 to 30 12), contact 223 (1), conductor 222, armature and contact of relay 233, contact 238 (1), armature and front contact of relay 239, contact 249 (1), conductor 221, contact 224, (1), contact 214 (11), winding of the 35 magnet of switch 220 to battery and ground. The magnet of switch 220 is energized in this circuit and moves out of position 1. The finder switch 220 continues to rotate until it reaches the position corresponding 40 to the calling line 205 of the second group. A circuit is then closed from battery through the winding of cut-off relay 261, right-hand winding and contact and armature of relay 260, contact 227, conductor 206, left-hand 45 winding of test relay 264, conductor 215, contact 223 closed in its off position, contact 213 (12) to ground. Relay 264 energizes as above described, the finder switch 220 is brought to rest in engagement with the calling line and sequence switch 250 is moved 50 into position 3 ready for the transmission of the tens series of impulses.

Since the called line belongs to the second group, the tens digit thereof is 2. Accordingly the calling subscriber transmits a series 55 of eight impulses to set the register 100 in position 8. Sequence switch 250 then moves from position 3 over positions 6 and 7 and into position 9, as described. In passing 60 through positions 4 and 5 sequence switch 250 closes a circuit for the energization of relay 274 which serves to determine the selection of the proper one of the two selective switches 280 and 290. This circuit 65 may be traced from battery through the

winding of relay 274, contact 282, contact 106 (8) of register 100, contact 254 (4 to 5), back contact and armature of relay 264 to ground. Relay 274 becomes energized and locks up over a circuit from battery through 70 the winding of said relay, contact 282, left-hand armature and contact of relay 274 to ground at contact 235 (3 to 17). The sequence switch 250 in passing through position 6 causes the restoration of register 100, as 75 above explained.

In position 9 of sequence switch 250, the units impulses are sent and register 100 is advanced to its second controlling position. After register 100 has been positioned the 80 sequence switch 250 advances into position 11. In position 11 a circuit is closed for the operation of the selective switch 280, which advances under the control of the register 100 to select the terminals of the called subscriber's line. This circuit leads from battery through the winding of the magnet of switch 280, front contact and right-hand armature of relay 274, back contact and armature of relay 262, contact 255 (11), back 90 contact and armature of relay 234, contact 235 to ground. Each time the switch 280 passes through one of its half positions contact 283 is closed. A circuit is established from battery through the winding 95 of register 100, contact 102, contact 283, contact 254 (11), back contact and armature of relay 264 to ground. Register 100 rotates from position to position in step with the switch 280 until it is restored to normal. 100 In position 0 of the register 100 a circuit is completed from battery through the windings of relay 234, contact 104 (0), contact 256 (11) to ground. Relay 234 operates and completes a circuit from battery through 105 the winding of sequence switch 250, contact 253 (11), front contact and armature of relay 234, contact 235 to ground. Sequence switch 250 advances from position 11 to position 13. From this point on the operation 110 involved in the completion of the connection is the same as that already described.

When the subscribers have replaced their receivers to the switchhooks after the completion of conversation, relays 268 and 262 115 become deenergized and relay 233 becomes energized. Sequence switch 250 is driven into position 17 by means of a circuit from battery through the winding of said sequence switch, contact 253 (16), contact and armature of relay 233, conductor 222, contact 223, contact 213 (12) to ground. In position 17 of sequence switch 250 a circuit is closed from battery through the magnet of switch 280, front contact and right-hand armature 120 of relay 274, back contact and armature of relay 262, contact 238 (17), contact and armature of relay 233, conductor 222, contacts 223 and 213 to ground. The switch 280 rotates back to its normal position, at which 125 130

time a circuit is closed from battery through the right-hand winding of relay 262, contact 105 (0), contact 293 (1), contact 283 (18 to 1), contact 254 (17), back contact and armature of relay 264 to ground. Relay 262 energizes in this circuit and completes a circuit from battery through the winding of sequence switch 250, front contact and armature of relay 262, contact 238 (17), and thence to ground at contact 213. Sequence switch 250, therefore, advances into its normal position 1.

The next time the finder switches 210 and 220 are taken for use, the switch 220 is first driven to its normal position 1 from the position in which it was left in connection with the last call. With finder 220 restored to its normal position, the finder 210 is then started in operation in the manner described 20 to find the calling line, provided such line is one of the first group of lines. If the calling line, however, belongs to the second group, finder 210 first makes a complete revolution to position 12, whereupon the 25 finder 220 again is set in operation to find the calling line in the second group. The circuit for restoring the finder switch 220 to its normal position may be traced from battery through the winding of the magnet 30 of said finder, contact 224 (2 to 11), conductor 221, contact 249 (1), front contact and armature of relay 239, contact 238 (1), contact and armature of relay 233, conductor 222, contact 223, contact 213 (12) to ground.

As hereinbefore stated, positions 2 and 4 of the selective switch 290 are reserved for central office connections. Two trunks 270 and 271 leading to the central office are shown as connected to contacts 297, 298 and 40 299 of switch 290 in positions 2 and 4 respectively. In order to make a central office, the calling subscriber operates his dial to transmit ten impulses. In response to this series of impulses the register 100 makes a 45 complete revolution and stops in position 0. When, therefore, the sequence switch 250 passes through positions 4 and 5 in the manner explained, a circuit is completed from battery through the winding of the magnet 50 of switch 290, contact 103 (0), contact 254 (4 to 5), back contact and armature of relay 264 to ground. The switch 290 advances into position 2 where the central office trunk 270 is tested. The test circuit for this purpose may be traced from the test conductor 272, contact 299 (2), conductor 232, contact 246 (4 to 16), through the left-hand winding of test relay 264, contact 256 (7) to ground. The sequence switch 250 will have 55 moved over position 6 and into position 7 in the manner hereinbefore described. If trunk 270 is found idle, relay 264 energizes. Relay 264 including its right-hand winding and the test circuit reduces the potential on 60 test conductor 272 in order to render the

trunk busy to other switches. When the sequence switch 250 passes through position 6 relay 234 energizes in a circuit from battery through the windings of said relay, conductor 229, contact 104 (0), contact 256 (6) to ground. Relay 234 remains locked up in position 7 of sequence switch 250 by means of a circuit from battery through the windings of said relay, resistance 212, contact 236 (7), front contact and armature of relay 234 to ground at contact 235. The calling subscriber's line is connected through to the central office trunk 270 with sequence switch contacts 244 and 245 closed in position 7, and the further extension of the call 80 may be made in the usual manner.

At the completion of conversation the calling subscriber by replacing his receiver on the switchhook causes the deenergization of supervisory relay 268. Relay 233 thereupon energizes by means of a circuit from battery through the windings of said relay, contact and armature of relay 268, armature and back contact of relay 231, contact 236 (7), front contact and armature of relay 234, contact 235 to ground. Relay 233 completes a circuit from battery through the winding of sequence switch 250, contact 253 (7), contact and armature of relay 233, conductor 222, and thence to ground at contact 213. Sequence switch 250 moves into position 9. In position 9 of sequence switch 250 relay 234 is energized by means of a circuit from battery through the windings of said relay, resistance 212, back contact and armature of relay 231, contact 243 to ground. Relay 234 completes a circuit from battery through the winding of sequence switch 250, contact 253 (9), front contact and armature of relay 234 to ground at contact 235. Sequence switch 250 moves out of position 9 and into position 10. In position 10 of sequence switch 250 a circuit is completed from battery through the winding of the magnet of switch 290, back contact and right-hand armature of relay 274, back contact and armature of relay 262, contact 238 (10), contact and armature of relay 233 to ground at contact 213. Switch 290 restores to its normal position, at which time relay 262 is energized in the manner above described. Relay 262 by attracting its armature closes a circuit from battery through the winding of sequence switch 250, front contact and armature of relay 262, contact 238 (10), contact and armature of relay 233, and thence to ground at contact 213. Sequence switch 250 thereupon advances into position 11. In this position a circuit is closed from battery through the winding of sequence switch 250, contact 253 (11), front contact and armature of relay 234 to ground at contact 235. Sequence switch 250 moves from position 11 into position 13. In position 13 of sequence switch 250 relay 262 125

130

is energized in a circuit from battery through the right-hand winding of said relay, contact 105 (0), contact 293 (1), contact 283 (1), contact 254 (13), back contact and armature of relay 264 to ground. Relay 262 closes a circuit from battery through the winding of sequence switch 250, front contact and armature of relay 262, contact 238 (13), contact and armature of relay 233, and thence to ground at contact 213. Sequence switch 250 moves into position 15 where a circuit is closed from battery through the winding of sequence switch 250, contact 253 (15), front contact and armature of relay 234 to ground at contact 235. Sequence switch 250 advances into position 16. In this position of sequence switch 250 a circuit is completed from battery through the winding of said sequence switch, contact 253 (10), contact and armature of relay 233 to ground at contact 213. Sequence switch 250 thereupon moves into position 17. In this position relay 262 is energized in the circuit above traced and completes the circuit already described for driving sequence switch 250 into its normal position.

What is claimed is:

1. In a telephone system, a plurality of selective switches for establishing telephone connections, a multi-position register, means for sending series of current impulses, impulse mechanism responsive to one of said series of impulses for variably setting said register, means controlled by said register when in its set position for selecting one of said switches, said impulse mechanism being responsive to another series of impulses for again setting said register, and means controlled by said register in accordance with its subsequent setting for operating the selected switch.
2. In a telephone system, a plurality of selective switches for establishing telephone connections, a multi-position register, means for sending series of current impulses, impulse mechanism responsive to one of said series of impulses for variably setting said register, means controlled by said register when in its set position for selecting one of said switches, means for thereupon restoring the register to its normal position, said impulse mechanism being responsive to another of said series of impulses for again setting said register, and means controlled

by said register in accordance with its subsequent setting for operating the selected switch.

3. In a telephone system, subscribers' lines, selective switches for interconnecting said lines, a multi-position register, means for sending series of impulses over said lines, impulse mechanism responsive to one of said series of impulses for variably setting said register, means controlled by said register when in its set position for selecting one of said switches, said impulse mechanism being responsive to another series of impulses for again setting said register, and means controlled by said register in accordance with its subsequent setting for operating the selective switch.

4. In a telephone system, subscribers' lines, selective switches for interconnecting said lines, a multi-position register, means for associating said register with a subscriber's line, means for sending series of impulses over said line, impulse mechanism responsive to one of said series of impulses for variably setting said register, means controlled by said register when in its set position for selecting one of said switches, said impulse mechanism being responsive to another of said series of impulses for again setting said register, and means controlled by said register in accordance with its subsequent setting for operating the selective switch.

5. In a telephone system, subscribers' lines arranged in groups, a plurality of selective switches one individual to each of said groups for interconnecting the subscribers' lines, a multi-position register, means for associating said register with a subscriber's line, means for sending series of impulses over said line, impulse mechanism responsive to one of said series of impulses for variably setting said register, means controlled by said register when in its set position for selecting one of said switches, said impulse mechanism being responsive to another of said series of impulses for again setting said register, and means controlled by said register in accordance with its subsequent setting for operating the selected switch.

In witness whereof, I hereunto subscribe my name this 14th day of January, A. D., 1920.

LIPA POLINKOWSKY.
